UNITED STATES PATENT OFFICE

172,821

TOY ARROW

Max L. Cass, Arcadia, Calif.

Application May 4, 1953, Serial No. 24,837

Term of patent 14 years

(Cl. D34—15)

To all whom it may concern:

Be it known that I, Max L. Cass, a citizen of the United States, residing at Arcadia, in the county of Los Angeles and State of California, have invented a new, original, and ornamental Design for a Toy Arrow, of which the following is a specification, reference being had to the accompanying drawing, forming part thereof, and wherein:

Fig. 1 is a perspective view of a toy arrow, showing my new design;

Fig. 2 is a top plan view thereof; and

Fig. 3 is an enlarged front elevational view thereof, partly in section, along line 3—3 in Fig. 2, the leading end being broken away for convenience of illustration.

I claim:

The ornamental design for a toy arrow, substantially as shown and described.
